UNITED STATES PATENT OFFICE.

WILFRED ROTHERY WOOD, OF LONDON, ENGLAND.

UNDERFEED-FURNACE.

No. 818,010.

Specification of Letters Patent.

Patented April 17, 1906.

Application filed March 25, 1904. Serial No. 200,046.

To all whom it may concern:

Be it known that I, WILFRED ROTHERY WOOD, a citizen of the United States of America, residing at London, England, have 5 invented a certain new and useful Improvement in Underfeed-Furnaces, of which the following is a specification.

It is common at the present time to feed fuel to furnaces by means of a screw conveyor or pusher delivering the green fuel to the bottom of a magazine or retort, the fresh fuel entering beneath that already partially coked. It is also common to provide such furnaces with movable grate-bars and to 15 provide suitable draft-inlets.

The present invention relates to improvements in apparatus of the general class above indicated, and the nature of the same will be understood from the following description, 20 reference being made to the accompanying drawings, in which—

Figure 1 is a longitudinal sectional elevation on the line 1 1 of Fig. 2, the motor-cylinder, cross-head, upstanding rib, and lug hereinafter mentioned being shown, however, in elevation; Fig. 2, a plan view with grate-bars on one side of the furnace only; Fig. 3, a sectional elevation on the line x x, Fig. 2; Fig. 4, a side elevation with some of the parts 30 omitted; Fig. 5, a detail cross-section on w w of Fig. 4; Fig. 6, a sectional elevation on the line z z of Fig. 2, but showing grate-bars on both sides; and Fig. 7 is an enlarged sectional view of the grate-bars themselves and of the 35 rocking bar.

Beneath the usual feed-hopper 1 is a fixed bed-plate 2, upon which works the pusher 3, the length and shape of which is so proportioned as to practically close the bottom of 40 the hopper when in its innermost position. Beneath the fixed plate 2 is a movable plate 4, which at its inner end forms the bottom of 45 the fuel-magazine 5 and carries the fuel into same, said plate being also provided with pushing-faces 16, rising, mound-like, therefrom, the inner faces being at approximate 50 right angles to said plate and the top rounded off downwardly thereto, while the outer faces from the crown form gentle declines, 55 with the object of securing a good and even forward feed of fuel in contradistinction to a simple banking-up process in the front of the furnace and also to slightly raise and agitate the fuel as the plate moves backward and forward within the side walls 17 of the retort-chamber, said side walls at the top being pro-

vided with outwardly-turned flanges upon which the grate-bars, hereinafter described, move or rest.

The bottom of the retort-chamber is surrounded by a draft-box 18, from which the draft passes through the twyer-openings 181 on the inner ends of the grate-bars 14 and also through the bars themselves, as indicated by the arrows, into the inclosed ash-pit 19, and thence up through the tipping side grates 20 and also between the bars 14, which are of box-like form.

The movable plate 4 is provided at its outer end with an upstanding rib 6, adapted 70 to fill a corresponding slot in the fixed plate 2, and from such rib or movable plate projects a lug 7, engaging with the pusher. In Fig. 1 the upstanding rib 6 is shown as being nearly at the back of slot in the plate 2, and this is its position when the pusher is at the outer end of its stroke. The engagement is preferably by means of the lug bearing against a face 8 of the pusher for motion in one direction and of adjusting-screw 9, 80 which passes through the lug, bearing upon the wall of the opposite end of the pusher. By this means the pusher may be made to have the same longitudinal motion as the movable plate or a certain amount of lost 85 motion, as may be desired. In either event the fixed plate 2 prevents the feed-plate 4 carrying back the fuel delivered to it.

Motion may be imparted to the movable plate by means of a depending yoke 10, engaging with the piston-rod 11 of a motor-cylinder 110, and the reciprocating motion so obtained is converted into reciprocating motion for the grate-bars 14 at right angles to that of the movable plate 4 by supplying 95 such plate with grooved guide pieces or nuts 12, which through spiral feathers or projections 22 impart a rocking motion to bars 13, which in turn operate the grate-bars 14. The grooves in 12 are preferably cut spirally 100 or curved, and the feathers 22 are similarly formed, so as to be adapted to engage therewith, so as to impart a rocking motion to the bars 13 and through them to the rocking bars proper, 13, which beneath the grates are 105 either pivoted at their base or preferably made of double-bulb section, the lower bulb resting in a suitable recess in the casing, while the upper one engages with notches 15 in the grate-bars to be rocked or moved, as most 110 clearly seen in Figs. 6 and 7.

The feathers 22, operated by the nuts 12,

may be formed directly on rocking bars 13; but it is more convenient to have separate shafts and couple them with the bars by another bar 21, Fig. 5, adapted to drop into recesses in the bars and shafts, as this construction enables the movement of the grate-bars on one side of the furnace to be readily stopped while those on the other side continue to operate.

10 If desired, certain of the grate-bars—as, for instance, alternate ones—may be fixed.

By reference to the drawings, particularly Fig. 6, it will be seen that by properly proportioning and positioning the rocking bars 13 and the grate-bars, with which they engage, with relation to each other it is possible to impart a simple reciprocating movement to the grate-bars, or they may also be given a rising-and-falling movement. Thus 20 the depth of the notch 15 in a grate-bar may be made such that the bar 13 will bear only against its sides. The grate-bar will then have simple reciprocating motion. If, however, the depth of the notch is such that it is 25 engaged by the top of the bar 13, the grate-bar will, in addition to its reciprocating motion, be caused to rise and fall as the bar 13 is rocked back and forth.

With the construction indicated it will be 30 noted that when it is desired to move more or less of the fuel to the back of the retort-chamber this can be secured by adjusting the stroke of the pusher relative to that of the bottom plate, while, if desired, the full quantity 35 of fuel fed in a given period can at the same time be secured by quickening the stroke, and this through the rocking bars 13 will give increased rapidity of motion to the grate-bars 14, which will rapidly carry out 40 the fuel from the retort-chamber while giving full admission of the draft, thus securing a speedy coking and effective and almost smokeless combustion.

The object in making the grate-bars of box-like cross-section, with end openings only and 45 without direct openings on the furnace side, is to insure that all the blast shall first pass to the point where the heat is greatest—namely, at the retort end—and that such portion as is 50 not required for the retort shall pass the whole length of such grate-bars down into the ash-pit, from whence it rises between the bars and to the side grates when they are employed. This construction not only insures 55 the cooling of the bars where most likely to burn out, but also increases the heat of the blast which passes to the coked fuel from the ash-pit.

I am aware that it has heretofore been proposed to employ a feed-plate forming more or less of the furnace-bottom, and I do not in the present application claim such construction, for other known methods of feeding the fuel to the retort may be employed. I am 65 also aware that it has been proposed to re-

ciprocate grate-bars both longitudinally of the furnace and at right angles thereto by means of cams or equivalent mechanism; but from practical experiment I have found that the construction hereinbefore described by 70 which the grate-bars may not only be reciprocated, but also raised and lowered, if desired, is extremely effective and durable.

What is claimed is—

1. In underfeed-furnaces and in combination, a retort, means for feeding the fuel thereto, grate-bars of box-like cross-section each having one end in proximity to the retort, said grate-bars being adapted to take all the air to support combustion at their retort 80 ends and to deliver a portion to such retort and all the remainder to the ash-pit, and an inclosed ash-pit adapted to receive said air, substantially as described. 75

2. In underfeed-furnaces and in combination, a retort, means for feeding the fuel thereto, grate-bars of box-like cross-section each having one end in proximity to the retort, said grate-bars being adapted to take all the air to support combustion at their retort 85 ends and to deliver a portion to such retort and all the remainder to the ash-pit, an inclosed ash-pit adapted to receive said air, and means for reciprocating the grate-bars substantially as described. 90

3. In underfeed-furnaces and in combination, a retort, means for feeding the fuel thereto, grate-bars of box-like cross-section each having one end in proximity to the retort, said grate-bars being adapted to take all the air to support combustion at their retort 100 ends and to deliver a portion to such retort and all the remainder to the ash-pit, an inclosed ash-pit adapted to receive such air, and tipping grates at the outer ends of said 105 grate-bars, substantially as described. 95

4. In underfeed-furnaces and in combination, a retort, means for feeding the fuel thereto, grate-bars of box-like cross-section each having one end in proximity to the retort, said grate-bars being adapted to take all the air to support combustion at their retort 110 ends and to deliver a portion to such retort and all the remainder to the ash-pit, an inclosed ash-pit adapted to receive said air, 115 means for reciprocating the grate-bars and tipping grates at the outer ends of said grate-bars, substantially as described. 120

5. In underfeed-furnaces and in combination, a retort, means for feeding the fuel thereto, grate-bars of box-like cross-section each having one end in proximity to the retort, said grate-bars being adapted to take all the air to support combustion at their retort 125 ends and to deliver a portion to such retort and all the remainder to the ash-pit, an inclosed ash-pit adapted to receive said air 130 rocking bars adapted to reciprocate said grate-bars and means for rocking said rocking bars, substantially as described. 130

6. In underfeed-furnaces and in combination, a retort, means for feeding the fuel thereto, grate-bars of box-like cross-section each having one end in proximity to the retort, said grate-bars being adapted to take all the air to support combustion at their retort ends and to deliver a portion to such retort and all the remainder to the ash-pit, an in-
closed ash-pit adapted to receive said air,
rocking bars, notches on the grate-bars with

which said rocking bars engage, and means for operating the rocking bars, substantially as described.

In testimony whereof I have hereunto set my hand in the presence of two subscribing ¹⁵ witnesses.
